J. H. Richards

UNITED STATES PATENT OFFICE.

JUSTUS A. TRAUT, OF HARTFORD, CONNECTICUT.

CLASP.

SPECIFICATION forming part of Letters Patent No. 511,820, dated January 2, 1894.

Application filed July 23, 1891. Serial No. 400,423. (No model.)

To all whom it may concern:

Be it known that I, JUSTUS A. TRAUT, a citizen of the United States, residing at New Britain, in the county of Hartford and State of Connecticut, have invented certain new and useful Improvements in Clasps, of which the following is a specification.

This invention relates to that class of clasps in which one part is attachable to the other by means of a hook or catch operable by the fingers, and which are applicable to garters and to suspender-buckles.

In the drawings accompanying and forming a part of this specification, Figure 1 is a front view of my improved clasp, illustrating, also, its application to a suspender-buckle. Fig. 2 is a vertical section of the same in line *a a* of Fig. 1. Fig. 3 is a back view of the frame of the clasp. Fig. 4 is an end view of the frame. Fig. 5 is a front view of the clasp-slide. Fig. 6 is a front view of the clasp of a form adapted to be used as a garter-clasp. Fig. 7 is a sectional view of the slide taken on dotted line *b, b* Fig. 5.

Similar characters designate like parts in all the figures.

The improved clasp herein shown and described consists essentially of an open frame constructed to receive the slide, and the slide fitted to engage between parallel guides carried by the side bars of the frame.

The clasp-frame, designated in a general way by *F*, consists of the lower and upper front cross-bars *3* and *5*, respectively, connected at their ends by the parallel side-plates which have their outer edges bent first backward and then inwardly to form the grooved slide-guides *6* and *8* for receiving the slide. Said frame-plate has an open front between said cross-bars and side-plates of less width than the frame, and the spring-slide which is fitted to slide in said guide-grooves has the depending spring thereof bent forward in position for engaging on the upper edge of said lower cross-bar, the side portions of said depending point of the spring-slide constituting stops engaging behind the inner edges of said side-plates of the frame. At its upper end, (so called as a matter of convenience, notwithstanding the clasp may be used horizontally,) the frame is to be provided with

means for attaching it to the strap or article carrying the clasp. For instance, in Figs. 1, 2 and 3 the frame is shown by the dotted lines extending upwardly to form the usual lever-plate, *L*, of a suspender-buckle; while in Fig. 6 said frame has, as shown by the dotted lines, the usual double loop, *9*, of a garter-clasp. In Figs. 1 and 2 the buckle-frame usually used in connection with the lever *L* is shown at *M* by dotted lines.

The clasp-slide, or spring-slide designated in a general way by *S*, is furnished at its lower end with means, as the loop *21*, for carrying the strap or like part to be supported, and is fitted to slide into the grooves *10* and *12* formed between the aforesaid side bars *2* and *4* and their guides *6* and *8*, respectively. The slide is bent over upon itself at the line *13*, to form the slide-spring *14*, whose lower end constitutes the slide-catch *15* and is adapted to engage the upper side of the cross-bar, *3*, of the clasp-frame; said spring being for this purpose properly shaped at the lower end, to form the slide catch *15*, by having the middle portion of its width struck up or thrown forward out of the plane of the side edges of the slide spring *14* to engage said cross-bar, while the side portions, being relatively thrown backward, lie under the side bars of the frame to serve as stops for limiting the forward or outward movement of the spring *14*.

According to my invention the spring portion *14* of the clasp slide is swaged or struck up at its lower end on lines *17*, *18*, which lines are somewhat remote from the side edges of said spring portion, and the middle portion *15* thereof is thrown forward out of the plane of the side edges *19*, *20*, of the said spring portion *14*, to thereby form the slide catch which will, when the parts are assembled as shown in Fig. 2 of the drawings, have its lower edge in substantial alignment with the lower cross-bar *3* of the frame and be adapted for engagement therewith to prevent longitudinal displacement of the slide. By forming the slide catch in this manner, an important advantage is attained, to wit:—The parallel portions *19*, and *20*, at either side of the struck-up slide-catch *15* form longitudinal guides therefor which underlie the side bars *2*, *4*,

of the frame and prevent lateral displacement of the slide catch, thus insuring the positive engagement thereof with the lower cross-bar 3 of said frame.

- 5 In using the clasp, the operator, to connect the two parts thereof, has only to enter the folded end 13 of the slide into the grooves 10 and 12 at the lower end of the clasp-frame, and then to push the slide upward until the 10 catch 15 engages the upper edge of the cross-bar 3, as shown, for instance, in Figs. 1 and 2. The parts being clasped together as set forth, to detach the same the operator with his fingers seizes the clasp-slide upon the back and 15 front sides thereof, and closes the spring 14 upon the slide-plate 16 to disengage the catch 15 from said lower cross-bar, when by pulling on the slide this will be drawn from the frame and from between the operator's fingers. In 20 grasping the slide as aforesaid, the operator bears upon the slide-plate 16 between the guides 6 and 8, respectively, of the frame, and with one finger bears upon the front surface

of the slide-spring 14 through the opening 20 of the frame.

Having thus described my invention, I claim—

The herein described slide-clasp, it comprising the loop-shaped frame F having the upper and lower front cross-bars connected 30 by the parallel integral side plates which have their edges bent backwardly and then inwardly to form the guide-ways for the slide, in combination with the U-shaped spring-slide S having the extreme end of its spring-portion struck-up or thrown forward in the 35 middle portion of its width to form a slide-catch extending outward beyond the plane of the edge portions of said spring, and adapted when the parts are assembled for engaging 40 with the upper edge of the lower cross-bar of the frame, as set forth.

JUSTUS A. TRAUT.

H. MALLNER,
HENRY L. RECKARD.

Correction in Letters Patent No. 511,820.

It is hereby certified that the residence of the patentee in Letters Patent No. 511,820, granted January 2, 1894, upon the application of Justus A. Traut, for an improvement in "Clasps," was erroneously written and printed at the head of the specification, "Hartford, Connecticut," whereas said residence should have been written and printed *New Britain, Connecticut*; and that the said Letters Patent should be read with this correction therein that the same may conform to the record of the case in the Patent Office.

Signed, countersigned, and sealed this 16th day of January, A. D. 1894.

JNO. M. REYNOLDS,

Assistant Secretary of the Interior.

[SEAL.]

Countersigned:

JOHN S. SEYMOUR,

Commissioner of Patents.
